ABSTRACT OF THE DISCLOSURE

A remote thermometer having a charged bulb disposed within a well. The well is provided to isolate the fluid system under test from the ambient atmosphere. The well is projected into a large steam pipe or liquid tank, and the thermal bulb may then be inserted into the well to sense the steam or liquid temperature. The bulb can be removed or replaced at any time without disturbing the well or otherwise allowing the steam to escape into the ambient atmosphere.

Summary

The invention is directed to a bulb locking mechanism which is usable with various well sizes, which firmly retains the bulb in thermal engagement with the well end wall, which is easily installed in and removed from the well, and which is manufacturable at relatively low cost.

The drawings

FIG. 1 is a longitudinal sectional view of a bulb-well assembly having one embodiment of the invention incorporated therewith. The assembly is shown in association with a remotely-located read-out means containing a pressure-responsive diaphragm, bellows, etc.

FIG. 2 is an enlarged side elevational view of a clamping element usable in the FIG. 1 apparatus.

The drawings in greater detail

FIGURE 1 shows a vessel or passage wall 10 which may in actual practice be a large steam pipe, refrigeration line, refrigeration tank, brine tank, or other container for a liquid or gaseous media 12 of temperature changing characteristics. The temperature may for example range from -40° F. to +180° F. or from 400° F. to 1200° F., depending on the particular installation. Wall 10 is shown with an opening 14 therethrough for accommodating a well 16 used to contain a thermal bulb 18, formed for example of stainless steel. Bulb 18 is provided with a closed end wall 20 and a tubular side wall 22 which telescopes over a plug-like adapter 24, a suitable heliarc weld being employed to secure the bulb and adapter together.

Attached to the reduced end portion of adapter 24 is a tubular sleeve 26 which forms part of a fluid conduit means designated generally by numeral 28. Sleeve 26 has an enlarged diameter at its opposite ends and a reduced diameter in its mid-portion, the reduced diameter portion extending for a considerable distance, as for example 12 or more inches. Sleeve 26 forms what is sometimes termed a bendable extension, its elongated length enabling it to be bent or curved at right angles at different selected points therealong, depending on the position of wall 10 in relation to the outer panel or surface behind which wall 10 is located.

Extending within sleeve 26 is a filler tube 30 and a capillary tube 32, the filler tube being used to charge the bulb 18 to a suitable pressure or level with a suitable thermal charge, which may be a gas or volatile liquid, depending on the temperature range of media 12 and the desired pressure change per unit tempera-

2

ture change. Capillary 32 extends through sleeve 26 into a conventional flexible armor 32, said armor having a crimped and soldered connection with sleeve 28. The armor and shielded capillary tubing extend to a cup-like gage housing 34 having a conventional diaphragm, bellows, or Bourdon coil mounted therein to communicate with the capillary tubing. Armor 32 and the contained capillary tubing may be of various lengths, as for example 10 feet or 125 feet, depending on the relative locations of fluid vessel 10 and the control panel which mounts gage 34.

The general operation of the gage involves a thermal expansion of the bulb material which is transmitted through the capillary tubing to the diaphragm, bellows, or Bourdon coil 34, suitable mechanism being provided in the gage to translate movement of the diaphragm, etc. into a visible rotation of the temperature indicating pointer 36. As is well known, the same general system can be used to operate an electric switch or control valve in lieu of the illustrated gage 34.

The present invention is concerned particularly with mechanism for retaining bulb 18 in well 16. The illustrated retaining mechanism comprises a nut 38 arranged to thread into a threaded opening in the mouth portion 40 of the well when a turning pressure is applied on the wrench flats 42. Nut 38 is provided with an internal annular convergent cam surface 44 of frusto-conical character, and an internal threaded surface designated generally by numeral 46. Cooperating with nut 38 is an annular clamping means configured to form an externally threaded section 48, a wrench flat section 50, and a frusto-conical cam surface 52.

As shown best in FIG. 2, the clamping element is provided with a diametrical slot 54 extending for a considerable portion of the clamping element length to form two deflectable sections 56 and 58. Internally the clamping element is provided with a cylindrical surface 60 extending from the left end of the element about two-thirds of the way toward the right end of the element. Second smaller diameter cylindrical internal surfaces 62 are formed in the rightmost portions of the clamping element, the normal clearance between surfaces 62 and the outer surface of sleeve 26 being on the order of a few thousandths of an inch, sufficient to permit the clamping element to slide freely along the surfaces of sleeve 26 when said element is disengaged from nut 38.

Assuming that bulb 18 has been inserted into well 16 so that its end wall 20 is in firm thermal engagement with end wall 21 of the well, the clamping element 47 can be threaded into nut 38, whereupon the cam surfaces 52 ride along the cam surface 44. During such movement the two deflectable sections 56 and 58 of element 47 are forced inwardly so that surface portions 62 firmly grip on sleeve 26, thus retaining the bulb within well 16.

The drawing shows a single well 16 of a given length. However, in practice the well length may vary depending on the nature of vessel 10, and the desired length of insertion of the bulb into media 12. The well length penetration (dimension 13) may for example vary from about 5 inches to about 8 inches, depending on the installation. The illustrated locking means formed by nut 38 and clamping element 47 is adapted for retention of the bulb in firm thermal engagement with end wall 21 irrespective of the well length. Thus, a given length bulb may be inserted into an 8 inch well or a 5 inch well, and the same clamping mechanisms 47 and 38 used to lock the bulb in place. The clamping is operative for lock purposes at any point along sleeve 26 so that no spacers or other positioning devices are needed to assure correct locking action with different length wells or bulbs.

It will be noted that slot 54 forms a path for flow of fluid between the space within well 16 and the ambient atmosphere. Thus, referring to FIG. 2, fluid located rightwardly of clamping element 47 can flow through slot 54 into the large interior chamber defined by surface 60, and thence into the space located leftwardly of element 47. In some cases this fluid flow path can be advantageously used to safely vent fluid from the well interior. For example, should the well develop a leak the venting path can release dangerous pressure build-ups which would otherwise be released onto the repairman's face. Sometimes water or other liquid is poured into the space between the well interior surface and bulb outer surface to improve heat transfer; in conventional arrangements the water when heated is apt to build up a pressure which can scald the serviceman while the bulb is removed from the well. With the vented arrangement it is of course not feasible to use a non-viscous liquid heat transfer medium between the well and bulb; instead a metal sleeve, viscous liquid, paste, copper wool, steel wool, etc. must be employed for such purposes.

Variations in arrangement, contour of parts, etc. can of course be.

It is claimed:

1. In combination: a mounting well for a thermal bulb; said well having a tubular side wall, an end wall, and an open mouth remote from the end wall; a temperature responsive power unit comprising a thermal bulb insertable through the open mouth into said well, and fluid conduit means extending from the bulb through the mouth; and means for retaining the bulb in the well, said retaining means comprising seat means forming an internal convergent cam surface and a threaded surface at the well mouth, and deformable clamping means movable along the cam surface to exert a clamping pressure on the fluid conduit means; said deformable clamping means comprising an annular clamping element having a threaded section meshable with the threaded surface

on the seat means, and a frusto-conical section engageable with the cam surface; said annular clamping element being split for a portion of its length to provide at least two spaced deflectable sections hingedly movable toward the fluid conduit means as the clamping element is threaded into the threaded surface on the seat means.

5 2. The combination of claim 1 wherein the seat means is formed by an annular nut screwable into the well mouth; said nut having an inner diameter at least as great as the outer diameter of the bulb to permit said bulb to pass therethrough.

10 3. The combination of claim 2 wherein the fluid conduit means comprises an outer armor-forming sleeve and an inner capillary tubing.

15 4. The combination of claim 2 wherein the nut is formed with a passage therethrough for venting of pressures from the space within the well externally of the bulb.

20 5. The combination of claim 2 wherein the annular clamping element is provided with wrench flats located externally of the seat means whereby a wrench can be applied to the wrench flats to turn and advance the clamping element into the seat means; the inner diameter of said annular element being substantially larger than the outer 25 diameter of the fluid conduit means except in those areas where the deflectable sections are adapted to clamp onto the conduit means; said annular element being split along its frusto-conical section and also along its threaded section whereby the deflectable sections are elongated in the 30 axial direction.
